ALFRED E. STAFFORD, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 727,014, dated May 5, 1903.

Application filed January 13, 1902. Serial No. 89,409. (No model.)

To all whom it may concern:

Be it known that I, ALFRED E. STAFFORD, a citizen of the United States, and a resident of Hopedale, county of Worcester, State of Massachusetts, have invented an Improvement in Automatic Filling - Replenishing Looms, of which the following description, in connection with the accompanying drawings, is a specification, like characters on the drawings representing like parts.

Looms provided with automatic filling-replenishing mechanism have heretofore been equipped with two independent devices to detect failure of filling, one of such devices controlling the operation of the replenishing mechanism and arresting the operation of the take-up. Inasmuch as this detecting device operated only on alternate picks, the second detecting device was employed to detect failure of filling on the other picks, and it was so connected with the take-up mechanism that the operation of the latter would be arrested upon detecting action, thus insuring arrest of the said mechanism when either device detected filling failure to prevent the formation of thin places in the cloth. Such apparatus forms the subject-matter of United States Patent No. 659,628, dated October 9, 1900, and the particular form of take-up mechanism provides also for let-back at the proper times.

The shuttle employed with filling-replenishing mechanism of the type shown in United States Patent No. 529,940 is provided with an automatically self-threading device at the end adjacent the thread-eye, and such end is the one nearest the outer end of the feeder or hopper of the replenishing mechanism, which latter is usually located at the right-hand side of the loom. In actual practice it sometimes happens that the filling breaks in the shed when the shuttle is traveling from right to left, and the end trailing from the shuttle will operate to tilt the fork of the detector at the left-hand side of the loom just as if the filling were intact; but on the next pick, the eye end of the shuttle then leading, the trailing end of filling will be drawn out of range of the right-hand fork, and the latter will detect filling failure. Such detection, however, only operates to arrest the take-up in the apparatus illustrated in Patent No. 659,628 on

the detected pick, and when the shuttle is next shot across the loom from right to left the trailing end is apt to again tilt the fork at 55 that side, so that no change of filling is effected, and this may continue for a number of picks until the trailing end of filling fails to tilt the fork which controls the replenishing mechanism. The loom continues to run with 60 the filling broken, and take-up is arrested every alternate pick only, so that when finally the filling is replenished and filling is again laid there will necessarily be a thin place in the cloth, and the longer the replenishing is delayed the greater will be the extent of such thin place.

In this invention, which relates particularly to automatic looms provided with two detecting devices, I have provided means to 70 insure the operation of the filling-replenishing mechanism upon filling failure, no matter whether detected by either or both of the detecting devices, thereby rendering impossible the delay in replenishing such as hereinbefore referred to and thin places resulting therefrom.

In accordance with my present invention the operation of the replenishing mechanism is directly controlled by one of the filling-detectors, as heretofore; but the detecting action of the other detector operates in an indirect manner to insure the actuation of the replenishing mechanism by or through the first-mentioned detector whether or not the latter detects the failure. The take-up mechanism, only a very small portion being herein illustrated, is controlled by both detectors, so that upon detection of filling failure by either detector take-up is arrested, substantially as in Patent No. 659,628.

The various novel features of my invention will be hereinafter fully described, and particularly pointed out in the following claims.

Figure 1 is a top or plan view, centrally broken out, of a portion of a loom provided with filling-replenishing mechanism and embodying one form of my present invention. Fig. 2 is an enlarged transverse section on the line 2 2, Fig. 1, looking toward the left, 100 to show a portion of the means for insuring the operation of the replenishing mechanism by detecting action of the auxiliary detector. Fig. 3 is a top or plan view of the mechanism

shown in Fig. 2; and Fig. 4 is a longitudinal section on the line 4 4, Fig. 3.

Referring to Fig. 1, the lay A³, shuttle-boxes B B^X thereon, the automatically self-threading shuttle S^X, having a thread-eye at its right-hand end, and the breast-beam A⁴⁰, having at one end the usual notched holding-plate N for the shipper S and at the other end supporting the filling-replenishing mechanism comprising a transferrer f' and a feeder F to contain a supply of filling-carriers b, may be and are all of well-known construction and operate in usual manner.

Any suitable take-up mechanism is included as a part of the organized loom—such, for instance, as shown in United States Patent No. 643,284—only the end a' of the pawl-carrier being herein shown, Fig. 2, having an upturned portion a¹⁰, by which, as will be described, the operation of the take-up is arrested upon filling failure.

The controlling rock-shaft d', which governs the operation of the filling-replenishing mechanism in well-known manner, is mounted in bearings 20 and has fast upon it an upturned arm d, having a lateral head d^X adjacent the outer end of a slide f^X, longitudinally movable in a guide f², transversely secured upon the breast-beam. A filling fork or detactor f of usual construction is pivotally mounted on the inner end of the slide, the tail f²⁰ being adapted to coöperate in usual manner with a notch 7 of the hook w of the weft-hammer W upon failure of the filling to tilt the fork, the said hook having a second notch 8, Fig. 4, for a purpose to be described. If the filling is not in front of the fork when the shuttle is in the box B, Fig. 1, the fork will not be tilted, and the slide f^X is moved outward, acting, through the arm d, to rock the shaft d' and effect a change of filling in well-known manner, and this direct acting mechanism is located at the left side of the loom, and for convenience this is termed the "main filling-detector." Rocking of the shaft d' in the direction of arrow 25, Fig. 2, as described, also acts, through a depending arm d², fast on said shaft, to move the take-up pawl-carrier a' to disengage the pawl from the usual ratchet, thereby arresting the take-up and permitting let-back, if the take-up mechanism is of that type, a lateral lug d³ on the arm d² engaging the upturned end a¹⁰ of the pawl-carrier. A stand g², secured to the breast-beam on the replenishing side of the loom, Fig. 1, has longitudinally movable therein a slide g^X, provided with an auxiliary filling detector or fork g, and when upon absence of filling the latter is not tilted its tail g²⁰ is engaged by the hook w^X of a weft hammer or actuator W^X and the slide g^X is moved outward. The outer end of the slide engages the upper end d⁴ of an arm d⁵, loosely mounted on the rock-shaft d', between two collars 16 17, fast thereon, the collar 17 having a shoulder 18 in the path of a shoulder d⁶ on

the hub of arm d⁵, the latter being held against the slide by a spring s^X. Enough lost motion between the shoulders d⁶ and 18 70 is permitted to effect the rotative movement of the rock-shaft d' upon outward movement of the slide g^X sufficient to arrest the operation of the take-up mechanism, but without turning said rock-shaft far enough 75 to effect the operation of the replenishing mechanism. Thus outward movement of either slide f^X or g^X will control the take-up mechanism and arrest its operation.

Sometimes when the filling fails as the shuttle is traveling to the box B the trailing end will be long enough to engage and tilt the fork f, so that filling replenishing will not be effected, while on the next pick the fork g will detect the failure and arrest the take-up. This detection is due to the fact that when the shuttle is in the box B^X the thread-eye is nearest the outer end of the box and the trailing filling is drawn out of the path of the detector g and the slide g^X is moved outward, rocking shaft d' and also moving the arm d outward. I have provided means herein whereby whenever the auxiliary detector detects filling failure the main detector-slide will be operated to effect filling replenishing 95 whether or not the main fork f is tilted, thus overcoming the objection referred to. A slide-bar e is mounted on the stand f² at one side of the slide f^X and held in place partly by a bracket e^X, secured to the stand, and partly 100 by a pivotal connection e' between the outer end of the slide-bar and the upper end d⁵ of the arm d, Figs. 2 and 3. A dog e² is fulcrumed at e³ on the slide f^X and extends rearwardly above the hook w, said dog having secured to it a yielding tongue e⁴, bent laterally at e⁵ to normally rest on the top of the slide-bar e, the latter constituting a detent to normally maintain the dog inoperative. When the shaft d' is rocked by outward movement of the slide g^X, as described, the movement of arm d is sufficient to draw the detent e outward far enough to release the tongue e⁴ and the dog e² drops, so that its tip will engage the notch 8 of the hook w, thus 115 constituting a connection between the slide f^X and weft-hammer W entirely independent of the detector f, and the slide f^X will be moved outward by the weft-hammer to thereby cause the operation of the replenishing 120 mechanism. The inner end of the detent e is beveled, as at 22, Fig. 2, to pass under the offset e⁵ and thereby lift the dog e² into inoperative position when the detent resumes its normal position relative to the dog. 125

Of course when the detector f detects filling failure the hook and tail f²⁰ will coöperate to effect movement of the slide f^X; but if the detector fails to detect then the proper movement of the slide is insured by the co-operation of the dog e² and the hook w, filling replenishing being effected in either case. The outer end of the tongue e⁴ is free and enters a hole e⁶ in the dog to permit compres-

sion of the tongue against the under part of the dog when the latter is in engagement with the hook w , because the outward movement of the slide f^x restores it to its normal position relative to the detent, the offset e^5 sliding up the incline 22 onto the top of the detent, and the instant the hook relaxes its pressure on the dog the latter is lifted by the tongue into inoperative position.

10 I have so constructed the slide and parts coöperating therewith that if the replenishing mechanism is operated a predetermined number of times in succession the loom will be stopped automatically. To this end the 15 open slide f^x has a cross-bar f^8 , Fig. 4, which supports a longitudinally-movable trip h , having its inner upturned end h' in the path of the weft-hammer and provided near its outer end with a depending lug h^2 , which rests 20 against an abutment f^{2x} , forming a part of the stand f^2 . An enlargement h^3 on the trip normally supports a cam-lump k^x on the under side of a finger k , fulcrumed at e^8 on the slide, and having its outer depending end k' 25 offset and hanging over the side of the stand. This end k' is normally above a knock-off lever n , fulcrumed at n' on the breast-beam, Fig. 1, and adapted to release the shipper from its holding-notch. The trip h has a recess h^8 in its upper face at its outer end, which is normally covered by a shield f^9 , forming a 30 part of the slide f^x , and a detent-pawl f^{10} , fulcrumed at f^{12} on the bracket e^x , normally rests on the shield above the recess, as in Fig. 4. 35 The first time the slide f^x is moved out the cam-lump k^x will be moved toward the outer end of the enlargement h^3 , the trip having been held from movement by the abutment f^{2x} , and when the slide moves in the trip moves with it, 40 the finger k' still being held up above the knock-off lever. The recess h^8 is then exposed, owing to the relative change in position of the trip h and shield f^9 , and if the slide is moved out on the next detecting-pick the shield 45 passes from under the pawl f^{10} and the point of the latter enters the recess h^8 and stops the trip, while the slide continues to move. This causes the cam-lump k^x to drop off the enlargement h^3 and the finger k' descends, but 50 in front of the knock-off lever. The slide returns, the trip moving with it, and the shield lifts the pawl out of the recess h^8 , while the finger k' rides up over the knock-off lever and drops behind it, so that if a third outward 55 movement of the slide takes place the knock-off lever is turned by the finger k' and the shipper is released to stop the loom.

If the shuttle threads properly after the first or second operation of the replenishing 60 mechanism, the weft-hammer will act upon the upturned inner end h' of the trip to return it to the position shown in Fig. 4, moving the finger k' into inoperative position thereby, and the same action of the weft-hammer restores the trip to normal relative 65 position on the slide when the loom is started after it has been stopped, as described.

My invention is not restricted to the precise construction and arrangement herein shown and described, as the same may be modified or rearranged in various particulars without departing from the spirit and scope of my invention.

Having fully described my invention, what I claim as new, and desire to secure by Letters Patent, is—

1. In a loom, take-up mechanism, two filling-detectors, connections between them and the take-up mechanism, to arrest the operation thereof upon detection of filling failure, filling-replenishing mechanism, one of the detectors directly controlling the operation of the same, and means whereby detection of filling failure by the other detector insures the operation of the detector which directly controls the replenishing mechanism.

2. In a loom, two filling-detectors, filling-replenishing mechanism the operation of which is directly controlled by one detector and indirectly by the other through the first-named detector, upon detection of filling failure, take-up mechanism, and connections between it and said detectors, whereby upon detection of filling failure the operation of the take-up mechanism is arrested.

3. In a loom, main and auxiliary filling-detectors, filling-replenishing mechanism directly controlled as to its operation by the main detector, means operative by or through detecting action of the auxiliary detector to cause filling replenishing through the operation of the main detector, take-up mechanism, and independent connections between it and said filling-detectors, to arrest the operation of said take-up mechanism upon detection of filling failure by either detector.

4. In a loom, two filling-detectors located at opposite sides of the loom, filling-replenishing mechanism directly controlled as to its operation by one of said detectors and indirectly by the other detector but through the first-named detector, upon detection of filling failure, and take-up mechanism the operation whereof is arrested by or through detecting action of either filling-detector.

5. In a loom, two filling-detectors located at opposite sides of the loom and adapted to detect filling failure on alternate picks, filling-replenishing mechanism controlled as to its operation by one of said detectors upon detection of filling failure thereby, means actuated by detecting action of the other detector to positively effect the operation of the first-named detector upon the next pick, and take-up mechanism the operation whereof is arrested by or through detecting action of either filling-detector.

6. In a loom, two filling-detectors located at opposite sides of the loom and adapted to detect filling failure on alternate picks, filling-replenishing mechanism at one side of the loom, directly controlled by the detector at the other side, means actuated by detecting action of the detector nearer said mechanism

to cause the operation of the latter by or through the directly-controlling detector, take-up mechanism, and independent connections between it and said detectors, to arrest 5 the operation of the take-up mechanism upon detection of filling failure by either detector.

7. In a loom, two filling-detectors, a slide for each, and an actuator for each slide, to move the latter operatively upon detection of 10 filling failure, filling-replenishing mechanism the operation whereof is directly controlled by operative movement of one of the slides, means governed by the other detector upon detection thereby of filling failure to cause 15 operative movement, by its actuator, of the directly-controlling slide, to thereby effect through said slide the actuation of the replenishing mechanism, and take-up mechanism the operation of which is arrested by or through 20 operative movement of either slide.

8. In a loom, a main filling-detector, its slide, an actuator to move the latter by or through said detector upon detection of filling failure, an independent and normally in- 25 operative connection between the slide and its actuator, filling-replenishing mechanism whose operation is effected by said slide, an auxiliary filling-detector, means governed by detection thereof of filling failure to render 30 operative said independent connection, and thereby cause filling replenishing by movement of the said slide, take-up mechanism, and controlling connections between it and the main and auxiliary filling-detectors.

35 9. In a loom, a main filling-detector, its slide, an actuator to move the latter by or through said detector upon detection of filling failure, an independent connection between the slide and its actuator, a detent to 40 normally maintain said connection inoperative, filling-replenishing mechanism controlled by or through the slide, an auxiliary filling-detector, means governed by detecting action thereof upon filling failure to withdraw 45 the detent and render said independent connection operative, whereby the slide will be moved to effect the actuation of the replenishing mechanism, and take-up mechanism controlled by or through both of said filling- 50 detectors.

55 10. In a loom, a main filling-detector, its slide, an actuator to move the latter by or through said detector upon detection of filling failure, a dog on the slide, to coöperate with the actuator, a detent to normally maintain the dog inoperative, filling-replenishing mechanism the actuation of which is effected through operative movement of the slide, an auxiliary filling-detector, means governed by 60 detecting action thereof upon filling failure to withdraw the detent and permit coöperation of the dog and actuator, to thereby effect operative movement of the slide and cause filling replenishing, and take-up mechanism controlled by or through both of said filling- 65 detectors.

11. In a loom, two filling-detecting devices

to detect filling failure on alternate picks, filling-replenishing mechanism the operation of which is directly controlled by one of said devices upon detection of filling failure thereby, normally inoperative means forming a part of said device to effect filling replenishing upon detection of filling failure by the other detecting device, controlling connections between the latter and said means, to render said means operative upon such detection of filling failure, and take-up mechanism the operation of which is arrested by or through filling failure detected by either 80 of said detecting devices.

12. In a loom, stopping means, filling-replenishing mechanism, means, including a main filling-detector, to effect the operation of said mechanism upon detection of filling 85 failure by said detector, and to operate the stopping means after a predetermined number of successive operations of said mechanism, an auxiliary filling-detector, devices operative by or through detection thereof to cause actuation of the replenishing mechanism through the means including the main detector, and take-up mechanism the operation whereof is arrested upon detection of filling failure by either detector. 95

13. In a filling-replenishing loom, in combination, filling-replenishing mechanism, take-up mechanism, two filling-detectors to detect filling failure on alternate picks, and means in connection with and operated by or through said detectors to arrest take-up and control the operation of the filling-replenishing mechanism when absence of filling is detected by either detector. 100

14. In a loom, two filling-detectors located at opposite sides of the loom, filling-replenishing mechanism controlled as to its operation by or through said detectors upon detection of filling failure by either, and take-up mechanism the operation whereof is arrested by or through detecting action of either filling-detector. 105

15. In a filling-replenishing loom, in combination, filling-replenishing mechanism arranged to effect the replenishment of the running filling-supply, take-up mechanism, filling-detectors at opposite sides of the loom, a rod or rock-shaft extending across the loom and having in connection therewith means operated thereby to arrest take-up and occasion the action of the filling-replenishing mechanism, and means operatively connecting said rod or rock-shaft with both of said filling-detectors whereby said rock-shaft is operated when either detector detects the absence of filling. 115 120 125

In testimony whereof I have signed my name to this specification in the presence of two subscribing witnesses.

ALFRED E. STAFFORD.
